(57) CLAIM

What is claimed is the ornamental design for a belt-wearable hook, as shown and described.

DESCRIPTION

FIG. 1 is a perspective view of a belt-wearable hook, showing a first embodiment of the new design;

FIG. 2 is a front elevational view thereof;

FIG. 3 is a rear elevational view thereof;

FIG. 4 is a right-side elevational view thereof, the left-side elevational view being a mirror image thereof;

FIG. 5 is a top plan view thereof;

FIG. 6 is a bottom plan view thereof;

FIG. 7 is a perspective view of a second embodiment thereof;

FIG. 8 is a front elevational view of FIG. 7, the rear elevational view being identical to FIG. 3;

FIG. 9 is a right-side elevational view of FIG. 7, the left-side elevational view being a mirror image thereof;

FIG. 10 is a top plan view of FIG. 7; and,

FIG. 11 is a bottom plan view of FIG. 7.

The broken lines in the figures denote that the design is of indeterminate length.
